WASTE AND OVERFLOW FITTING

Patrick F. Donahue, Waterbury, Conn., assignor
to Scovill Manufacturing Company, Waterbury,
Conn., a corporation of Connecticut

Application August 31, 1944, Serial No. 552,049

14 Claims. (Cl. 4—191)

1

The present invention relates to improvements in waste and overflow fittings for bath tubs and the like, and has for an object to eliminate the unsightly drain hole plates that have been customarily used over overflow fittings and substitute in place thereof an imperforate plate or cover shell combined with a concealed plate holder to the end that no openings appear externally in the plate to mar the appearance of the overflow fitting; the imperforate plate and its holder, which may be a casting or cast body, being so constructed and arranged relatively to one another as to provide overflow discharge openings rearwardly of the plate or rearwardly of a flange of the plate.

Another object of the invention is to provide an overflow fitting without the use of visible screws or other fastening means which is intended to confuse and confound the ordinary layman as to the construction and method of assembly and disassembly of the fitting unit to act as a deterrent to discourage the removal and stealing of drain plugs and chains and other parts of the fittings as is often done in hotels.

A further object of the invention is to provide an improved fitting for drains, overflows or the like in which the lack of external visibility of screws or fastenings and the imperforate character of the finish plate will impart an ornamentation and a finish that could not be obtained with slotted or perforated plates held in place by obvious screws or other fastenings.

The invention has for its further object to secure the above advantages by the use of a simple, economically manufactured construction capable of cooperating with usual drain and overflow fittings and involving a unitary construction which lends itself to ready installation and removal by the authorized and instructed.

A still further object of the invention is to provide an overflow unit so constructed and arranged as to lend itself to ready adaptation to the various angular positions that the wall of a bath tub may assume relative to the vertical axis of the overflow pipe.

With the foregoing and other objects in view, the invention will be more fully described hereinafter, and will be more particularly pointed out in the claims appended hereto.

Figure 1 is a vertical section taken through a portion of a bath tub and drain and overflow fittings and illustrated in edge elevation and constructed according to the present invention.

Figure 2 is a front elevation of the improved

fitting taken on an enlarged scale and with parts broken away and parts shown in section.

Figure 3 is a vertical cross section taken on the line 3—3 of Figure 2.

Figure 4 is a horizontal cross section taken on the line 4—4 of Figure 2.

Figure 5 is a perspective view of the cast body or plate holder, and

Figure 6 is a fragmentary vertical section taken through a portion of the bath tub wall, overflow pipe and the parts of the invention shown in disassembled relation.

Referring more particularly to the drawings 10 designates generally a bath tub having a drain 11 and an overflow 12. A conventional form of drain plug is shown as closing the drain 11 and as coupled to a customary captive chain 14.

As shown to best advantage in Figure 6 the bath tub 10 is formed with an overflow opening 15 with which the upper end of the overflow pipe 12 communicates. The upper curved or elbowed end of the overflow pipe 12 passes through registering openings 16 and 17 in a flanged retainer ring 18 and gasket 19 respectively. The gasket 19 is preferably of some compressible material and may be formed with a bevel seat 20 on its forward edge communicating with its central opening 17, such bevel edge conforming to, and adapted to receive thereagainst the outwardly flanged end 21 of the overflow pipe 12. There need be no bevel 20 in view of the fact that the rubber gasket will readily conform to any surface against which it is impressed.

The outer edge of the gasket 19 is formed in 35 two sections, a rear cylindrical section 22 designed and adapted to be confined by the flange 23 struck forwardly from the edge of the disc retainer ring 18; and a forward frusto-conical section 24 of a size and diameter to fit against the 40 rear edge of the overflow opening 15 of the bath tub 10. The flange 23 tends to avoid radial spreading of the gasket 19 except at its forward unconfined frusto-conical section where it may expand against the surrounding contacting portions of the wall of the bath tub opening 15 with the object of making a tight leak-proof joint.

The association of the retainer ring 18 and gasket 19 is to some extent found in the Pasman Patent 1,618,777 except that that prior patent 50 lacks the bevel seat 20, the rear cylindrical section 22 and the cooperative features with the overflow pipe part 21 and the flanged retainer ring 18 that these parts imply. Cooperating with the retainer ring 18 and gasket 19 and located at the 55 front side of the bath tub wall 10 is a face or

finish unit comprising the face plate 25 and the face plate holder 26.

The face plate holder may be a casting or a cast body. For convenience it may assume generally the form of a disc having a central opening 27 about a rear flange 28 which subserves two functions incident to the fact that both its internal and external walls are inclined. In fact the flange 28 may taper rearwardly, that is toward the overflow pipe, its outer tapering wall fitting within the outwardly-flanged end 21 of the overflow pipe 12 and acting to hold such pipe end firmly within its seat 20 in the gasket 19, as shown in Figure 3; and the inner tapering wall of the flange 28 acting to direct the overflow water from the tub into the overflow pipe 12, not through the gasket 19 or retainer ring 18 but directly from the flange 28 into the pipe 12. The mating relationship between the external wall of the frusto-conical flange 28 and the parts 21 and 20 also promotes the leak-proof character of the fitting.

The internal face of the holder or disc 26 is circularly shouldered as at 29 near its outer edge and is dimensioned so as to have a relatively loose fit within the opening 15 and serves to make it easier for the plumber to line up the casting 26 with the opening 15 on the tub during the assembly operation.

A cross bar 30 extends diametrically or otherwise across the central opening of the holder casting 26 to carry a threaded socket 31. A screw or threaded bolt carried by the face plate 25 is received into the threaded socket 31. The head 33 of the screw 32 is affixed non-rotatably in the face plate 25 and the external visible portion of such head which is revealed on the outside of the face plate 25 is preferably unslootted and may be given an ornamental character that would lead one away from any conclusion that the same is the fastening by which the face plate is secured in place.

Or the head 33 may be swivelly or rotatably mounted through the face plate 25 in which event the external visible portion of the head 33 may be provided with a cross cut or slot to receive a screw driver or other tool by which the same may be threaded into and out of the socket 31 without rotation of the plate 25. Where the plate 25 and screw 32 are affixed against relative rotation, the screw 32 will be threaded into and out of the socket 31 only by the rotation of the face plate 25.

As shown in Figure 5 the disc 26 is broken away or has a removed portion in order to expose the slots 34 at their ends to slide over the shanks of the attaching screws 35 and beneath the heads 36 thereof, the screw heads 36 being wider than the slots 34. As shown in Figure 5, the walls of the slots 34 are rounded off to facilitate guiding the holder 26 over the screws 35 upon assembly.

As shown in Figure 4 the screws 35 are threaded into threaded collars 37 on the flanged retainer ring 18 and such screws pass through the gasket 19 and retainer ring 18.

Lugs 38 project forwardly from the disc holder 26 near the peripheral edge thereof and in a widely spaced angular or circumferential relation. At the broken away or removed portion of the disc 26 a radial arm 39 carries a bifurcated lug 40, the legs of which are separated by the slot 41. The bifurcated lug 40 also projects forwardly and may be concentric with the lugs 38.

The lugs 38 and 40 receive thereagainst the rear surface of the face plate 25 in the assembled posi-

tion of the parts as shown in Figure 3. In this figure it is to be noted that the diameter of the face plate 25 somewhat exceeds that of the face plate holder 26 whereby the rear flange 42 at the edge of the face plate 25 clears the lugs 38, by a substantial margin, the centering of the face plate 25 upon its holder 26 being accomplished by the screw 32 in its relation to the threaded socket 31.

The lugs 38, 40 hold the face plate 25 away from the front face of the disc holder 26 and in effect provide between these parts an annular compartment or channel for the free flow of the overflow water from the tub 10. Such channel or compartment communicates with the interior of the tub 10 by the wide circumferential slits or openings between the lugs 38, 40 and at the cut away or removed portion of the holder disc 26.

If desired, the exterior surface of the rear holder flange 28 is preferably formed as a part of a spherical surface, over which surface the flanged end 21 of the overflow pipe 12 is capable of universal adjustment, within limits, so that the plate holder 26 will readily adapt itself to the various angular positions that the upright walls 10 of bath tubs may be disposed without effecting the vertical stand of pipe 12.

The parts 31 may be drifted apertures interiorly threaded for receiving the assembly screws 35, the heads of which are engaged against the front face of the cast body 26. The end ball of the drain plug chain 14 is engaged inside the perforated lug 40 before the face plate 25 is put in place and the link of the chain to the next ball is accommodated in the slot 41. The face plate 25 thus in an unrevealing manner locks the chain 14 against removal. The flange 42 of the face plate also fits between adjacent balls of the chain and tends to bind the chain between the face plate 25 and its holder 26.

In use, the overflow is caused to flow around the flanged edge 42 of the face plate 25 and then through the open center 27 of the cast body 26, and thence directly into the overflow pipe 12.

To assemble the device, the plumber initially assembles the screws 35 through the gasket and into the drifted threaded openings 37 of the retainer ring 18 but without tightening these screws 35 to any extent. The holder 26 is then assembled to the screws by bringing the mouths of the slots 34 under the screw heads 36 and sliding the plate edgewise until arriving at substantially the position shown in Figure 2 where such holder 26 is centrally oriented with respect to the bath tub opening 15, the upper end of the overflow pipe 12 and the other associated parts. The screws 35 can then be tightened so that the heads 36 clamp firmly against the outside surface of the disc holder 26. The screws 35 may be turned sufficiently to cause the flange 28 to bind tightly on the end 21 of the pipe and to draw the retainer ring 18 tightly up against the gasket 19 squeezing the gasket against both the pipe end 21 and the rear edge wall of the bath tub opening 15. Such screw pressure will also draw the disc holder tightly against the forward edge of the bath tub upright wall.

When initially sliding the disc holder 26 edgewise onto the screws 35, the screws will retain the holder disc 26 in place freeing one hand of the plumber to pick up a tool such as a screw driver wherewith to tighten the assembly screws 35. After the holder disc 26 is fastened in position the face plate 25 is assembled to the disc 26 by fitting the screw 32 to the socket 31 and

rotating the face plate suitably to cause threaded engagement between these parts; such engagement resulting in the feeding of the screw axially into the socket 31 and the concomitant progressive movement of the face plate bodily in an axial direction toward the holder 26 until in the home position face plate flange 42 overlaps disc lugs 38, 40 and slot 41.

When installed the unit exposes no visible screws but all that one sees is the entirely plain round ornamental flat plate 25 with a central spherical nub 33 which happens to be the head of the integral screw, but substantially concealing the fact that there is a screw associated with the plate.

The invention in one phase resides in the unit provided by the association of the face plate 25 and the holder member 26, and in this aspect it is immaterial what type of gasket or retainer ring or other member that may be used in rear of the tub to connect with the overflow pipe 12.

In a more specific aspect, the invention relates to the cooperation of the flange 28 of the holder member 26 with the end 21 of the pipe 12 and with the seat 20 of the gasket 19.

In still another aspect, the invention consists of that modification of the retainer ring 18 by which it is provided with the drifted threaded openings 37 in cooperation with the assembly screws 35 whereby these screws act in a treble capacity to first put the gasket 29 under compression against the edge of the bath tub wall opening 15, secondly to bind in a tight fit the disc holder rear wall that surrounds shoulder 29 against the bath tub wall, and thirdly to effect a squeezing together of the gasket 19 and holder plate 26 such as will bind the outwardly flanged end 21 of the overflow pipe 12 between these parts.

The presence of the flange 42 enhances the mystery of the construction and assembly of the fitting in that prying eyes or probing instruments are excluded thereby from gaining any access edgewise between the members 25 and 26, it being preferable that the depth of the flange 42 be sufficient comparably to that of the lugs 38, 40, to enable the flange 42 to extend over at least to the front surface of the holder member 26. The presence of the flange 42 also requires the water to flow forwardly or away from the wall 10 in order to get into the discharge opening 27.

It is obvious that various changes and modifications may be made in the details of construction and design of the above specifically described embodiment of this invention without departing from the spirit thereof, such changes and modifications being restricted only by the scope of the following claims.

What is claimed is:

1. In an overflow fitting, an imperforate face plate having a disc portion, and a perforated holder therefor having a disc portion with means to retain the disc portion of the face plate in spaced relation to the disc portion of the holder.

2. In an overflow and drain fitting for a perforated wall, a plate holder member, and an imperforate face plate member, means to hold the two members together, a drain plug captive element, and means between said plate and holder for fastening an end portion of said element.

3. In an overflow and drain fitting according to claim 2, said means comprising a bifurcated lug on the plate holder member to engage the free end of the element, and a flange on the plate to overlap the lug.

4. In an overflow pipe fitting, a backing member having an internal seat to receive an end portion of a pipe, and a front couple comprising an imperforate face plate, and a holder member therefor having a rearwardly directed flange to internally engage the pipe end and surrounding a discharge opening, and means on the holder to hold the face plate and holder together in such relation that overflow water may flow between the face plate and holder to said discharge opening.

5. An overflow pipe fitting as claimed in claim 4 characterized by the seat and outer wall of the flange being beveled.

15 6. For use with an apertured bath tub wall and an overflow pipe, a backing member having a seat for the external wall of the end of the pipe and closing against the rear edge of the aperture, a plate holder adapted to fit against the front edge of the aperture and having a discharge opening and a flange about the opening adapted to engage the internal wall of the end of the pipe end reposing on said seat, and means to draw the holder and backing member toward one another.

20 7. For use with an apertured bath tub wall and an overflow pipe, a gasket adapted to fit about the pipe end and against the rear edge of the aperture and having a substantially cylindrical outer edge section and an inclined wall section to engage the rear edge of the aperture, a flanged retainer ring adapted to be placed against said gasket with the flange enveloping the cylindrical section, and a front fitting connected to said retainer ring and lying in front of the aperture.

25 8. For use with an apertured bath tub wall and an overflow pipe with an outwardly-flanged end, a gasket adapted to fit about the pipe and having a bevel seat to receive said flanged end and also having a frusto-conical outer edge portion to engage the rear edge of the aperture, a retainer ring adapted to lie in rear of the gasket, and a front fitting connected to the ring and adapted to lie in front of the aperture.

30 9. The device of claim 8 characterized by drifted threaded collars in the ring engaged by assembly screws extending through the front fitting.

10. In an overflow fitting for a perforated wall, an imperforate face plate having a flange, and a perforated holder for the face plate having means to space the face plate from said holder and the flange from the wall.

35 11. For use with a perforated bathtub wall and an overflow pipe back of said wall, a face plate and holder both in front of said wall, said face plate being imperforate and having an imperforate flange extending toward said wall, said holder having an opening communicating with the overflow pipe through the wall perforation and also having circumferentially spaced lugs projecting toward the face plate within said flange for spacing the face plate and holder, said lugs of a size to also space the flange from the bathtub wall.

40 12. For use with a perforated bathtub wall and an overflow pipe back of said wall, a face plate and holder according to claim 11 further characterized by the fact that the headed ends of bolts carried by a backing plate behind the wall project forwardly through the wall perforation and are engaged in open-ended slots of the holder by a sidewise sliding movement of the holder before the screws are made tight to bind the holder in

place, the face plate concealing the heads of the screws.

13. For use with an apertured bathtub wall and a flanged overflow pipe section, four members associated together two in front of and two in rear of the bathtub wall and forming a front and a rear couple, said rear couple comprising a gasket fitted to the outside of the pipe section and its flange and a backing plate in rear of the gasket, said front couple comprising a face plate and a face plate holder, said holder having a rearward projection constructed and arranged to fit through the aperture in the bathtub wall and enter the flanged portion of the pipe section and having an outer wall portion on which the flange may be moved and adjusted, said holder having an opening therethrough communicating with the pipe section, adjustable fastening means carried by said backing plate and engaged by said holder for mutually drawing the holder and gasket against opposite sides of the bathtub apertured wall, said face plate being imperforate and removably carried by the holder for obscuring said fastenings and preventing water draining through said face plate, and circumferentially-spaced means on the holder for contacting the face plate to maintain both the holder and face plate in

spaced relation to permit water to flow radially between the holder and face plate to the opening in the holder.

14. The combination claimed in claim 13 wherein the outer wall portion of the projection on the holder is a section of a sphere.
